Atty's.

UNITED STATES PATENT OFFICE.

GEORGE W. BULLEY, OF AKRON, OHIO, ASSIGNOR TO THE MILLER RUBBER COMPANY,
OF AKRON, OHIO, A CORPORATION OF OHIO.

SOUND AMPLIFIER.

Application filed July 2, 1925. Serial No. 41,187.

To all whom it may concern:

Be it known that I, GEORGE W. BULLEY, a citizen of the United States, and resident of Akron, in the county of Summit and State of Ohio, have invented certain new and useful Improvements in Sound Amplifiers, of which the following is a specification.

My present invention relates to improvements in horns or amplifiers for radio receiving sets, and aims to provide an article of sufficient size to give substantial sound amplification while at the same time enabling it to be placed in a relatively small cabinet.

15 The invention consists in turning the neck of the horn back upon itself and causing it to enter the wall of the bell portion so that it is adapted to carry the loud speaker inside the bell.

20 The invention further includes the novel construction by which such horn may be readily manufactured.

An embodiment of the invention is illustrated in the accompanying drawing, in 25 which:—

Figure 1 is a side elevation of an amplifying horn partly broken away.

Fig. 2 is a face view.

Fig. 3 is a view with the parts of the 30 horn as they appear before assembly, partly broken away.

Fig. 4 is a sectional detail on line 4—4 of Fig. 1.

Referring by reference characters to this 35 drawing, the numeral 1 designates the bell portion of the horn, and 2 the neck. The bell portion is provided with an opening 1^a in one side thereof, and the neck portion is doubled back and provided with an angularly turned end 2^a which passes through the opening and is adapted to carry on its end within the bell, the ordinary loud speaker unit, conventionally indicated at 3.

40 The most convenient method of manufacture is to mold the bell and neck portions separately, of suitable material such as hard rubber, the line of junction, Fig. 1, being indicated by the transverse line 1^b, and the parts being adapted to be subsequently

connected, the end 2^a being slipped through 50 the opening 1^a in the bringing of the parts together.

The portion 2^a is made slightly tapered and designed to fit the opening with a tight or wedging fit, which will exclude air passage at the joint. I have found that the parts may be readily connected at the line of juncture by providing them with interengaging beads and grooves, as for example by forming the neck portion at its larger end 55 with an annular bead 2^c and the portion 1^b of the bell with an internal annular groove 1^c.

On warming (and thus softening) the interengaging edges by suitable means, such as a water bath, the bead may be snapped into the recess and after cooling a tight and permanent joint will be secured.

I have found that the projecting end and loud speaker unit located in the bell mouth, 70 does not appreciably impair the amplifying action, while with this arrangement I can secure greater amplification with a horn occupying a restricted space.

Having thus described my invention, 75 what I claim is:—

1. A horn or sound amplifier for radio receiving sets, having the neck thereof projected through one wall of the bell portion and terminating in the bell portion, and 80 adapted to carry the loud speaker unit.

2. A horn according to claim 1, in which the bell and neck portions comprise separate portions provided with means for connecting them together.

3. A horn or sound amplifier comprising a bell portion and a neck portion, one of said parts having an annular groove and the other an annular bead engaging the groove, said bell portion having an opening in its wall, and said neck portion being doubled back upon itself and provided with an angular turned end projecting through said opening.

45 In testimony whereof, I affix my signature.

GEORGE W. BULLEY.
